UNITED STATES PATENT OFFICE.

THOMAS J. CROOK, OF WICHITA, KANSAS.

HYDROCARBON-BURNER.

1,262,311.

Specification of Letters Patent. Patented Apr. 9, 1918.

Application filed October 15, 1917. Serial No. 196,595.

To all whom it may concern:

Be it known that I, THOMAS J. CROOK, a citizen of the United States, and resident of Wichita, in the county of Sedgwick and State of Kansas, have invented certain new and useful Improvements in Hydrocarbon-Burners, of which the following is a specification.

My invention relates to hydrocarbon burners, and more particularly to certain improvements concerning my Patent No. 1,238,003, granted August 21st, 1917.

The improvements consist primarily in devising a single burner in contrâ-distinction to one of the duplex or multiple type; devising a type of burner head with a maximum surface upon which the atmospheric air may exert a cooling effect; providing for a more complete attenuation of the gas which goes to make up the combustible mixture; mounting the overlying retort in a novel fashion so that it may be quickly dismantled; and providing an intake which will preclude back-firing.

With these and other objects in view, the invention comprises the arrangement and construction of parts shown in the accompanying drawings, hereinafter described, and embraced within the scope of the appended claims.

In said drawings:

Figure 1 is a perspective view of my invention;

Fig. 2 is a longitudinal sectional elevation of the burner;

Fig. 3 is a transverse view taken on the line 3-3 of Fig. 2;

Fig. 4 is a transverse sectional elevation taken along line 4-4 of Fig. 2, and

Fig. 5 is a perspective view of certain details of the mixing chamber.

Referring specifically to the drawings, 5 designates the burner head, which consists of an inverted U-shaped manifold 6 with a communicating transversely disposed inlet manifold 7, the burner head, in its entirety, being formed of a single casting. The outer wall 8 of the manifold 6 is placed a relatively short distance from the inner wall 9, and is provided on its top with a plurality of horizontally extending kerfs 10, and on its opposite vertical side with a plurality of vertically extending kerfs or flame openings 11, and it will be noted in this connection, if reference be made to Figs. 1 and 2 of the drawings, that the upper series of flame

openings 10 do not extend the entire length of the outer wall 8 of the manifold, in fact, they extend from a point adjacent one outer end of the manifold to a point directly above the inlet manifold 7, while the vertical openings 11 are arranged along the entire longitudinal extent of the manifold 6 upon opposite sides of the inlet manifold 7. In other words, the upper portion of the manifold 6 terminates with the inlet manifold 7, and from this point it merges to the left of the inlet manifold in the form of a single thickness of metal, and is fashioned into a housing or chamber 12 with its sides presenting a continuity of the side portions of the manifold 6, its end 13 closed and its bottom 14 open for the purpose of admitting air to the mixing chamber as will be presently explained. By virtue of constructing the burner head in the manner set forth, the maximum number of flame openings are provided in the outer wall of the manifold 6, and at the same time the inner imperforate walls 9 will be subjected to the cooling influence of the atmospheric air, thus preventing the burner head from becoming unduly hot.

Rising from the upper outer end of the manifold 6 is a short bracket 15 with an eye 16 having a nipple 17 projecting therethrough with one end adapted for connection with a suitable source of hydrocarbon supply and the other end coupled with a retort pipe 18 by means of the nut 19. This retort pipe is located directly above the upper series of flame openings 10 and terminates at its opposite end in a mixing chamber 20, at which point the usual nozzle, as 21, with its opening 22, is attached.

Steel wool 23, or other similar packing is introduced into the retort 18 to insure a positive vaporization of the hydrocarbon. The mixing chamber has the same general conformation as the housing 12, although it is constructed on a reduced scale and seated within the housing 12 with its lower end 24 open and communicating therewith. An opening 25 is preferably formed in the top of the mixing chamber 20 to permit the insertion of a wire or other instrument for the purpose of cleaning out the minute opening 22 of the nozzle 21, and this clean-out opening 25 may be closed by the screw-plug 26. Directly in advance of the outlet nozzle 21 of the retort 18, and slightly spaced therefrom, is an intake 27 which extends out

wardly from the wall of the mixing chamber, then downwardly, and finally inwardly, terminating at the inlet manifold 7, where it is preferably screw-threaded into the wall 5 of the latter as at 28.

The complete burner may be supported by legs as 29, or any equivalent devices, the idea being to sustain the device at a short distance from the particular means of support 10 in order to provide for the free admission of air to all of its parts.

In practical operation the nipple 17 is connected with a suitable source of kerosene or other similar hydrocarbon, and the kerosene 15 gravitates into the retort 18. A small quantity of alcohol is then placed in the two troughs 30, which are formed in the top of wall 8, below and just to one side of the retort, and this alcohol is ignited and the 20 heat arising therefrom serves to preliminarily vaporize the kerosene in the retort, so that it will be atomized through the opening 22 of nozzle 21 in the form of an exceedingly fine spray. At the same time, it will be understood 25 that the vaporized kerosene mixes with air in the mixing chamber 20, the air and vapor forming a combustible mixture which passes on through the intake 27 and then into the burner head proper, where it is 30 ignited and the flame issues through the different sets of kerfs. The flames from the upper set of kerfs 10 then take up the work of the alcohol and automatically superheat the kerosene in the retort 18 to the desired 35 degree. Simultaneously the flames are emitted from the vertical kerfs in the side of the burner, and besides giving the heat required for any special purpose, the flames issuing from the kerfs on the opposite sides of the 40 housing 12 manifestly heat the housing so that the air entering therethrough into the mixing chamber will be initially heated by the time it arrives at a point directly in front of the atomizing nozzle 21. In this 45 manner both the hydrocarbon and the air are heated and their admixture greatly facilitated. The novel form of intake not only prevents backfiring or puffing, but also serves to attenuate the gas or admixture so that 50 complete combustion will ensue.

What is claimed is:

1. In a hydrocarbon burner, the combination of a burner head having a main body portion and an offset portion, the burner 55 head in its entirety having spaced inner and outer walls, the inner walls being imperforate and the outer walls having flame openings, a mixing chamber disposed in immedi-

ate proximity to the offset portion of the burner head, an intake pipe connecting the 60 burner head with the mixing chamber, and an overlying retort.

2. In a hydrocarbon burner, the combination of a burner head having a main manifold, an auxiliary inlet manifold, a mixing 65 chamber, an overlying retort connected with said mixing chamber, and an intake connecting the mixing chamber with the auxiliary manifold, a portion of said main manifold having a reduced flame area and being extended so as to sustain the mixing chamber 70 and partially inclose the intake.

3. In a hydrocarbon burner, the combination of a burner head having a main manifold, and an auxiliary manifold, said main 75 manifold having a series of flame openings in its top and a series of flame openings on either side, the flame openings in the top terminating short of the length of the manifold while the flame openings in the sides extend 80 the entire length of the manifold, a mixing chamber, a retort arranged adjacent the top set of flame openings and discharging into the mixing chamber, and an intake pipe connected with the mixing chamber and discharging 85 into the auxiliary manifold.

4. A substantially inverted U-shaped burner head having spaced double walls, the inner wall being imperforate and the outer wall having main flame openings in its opposite sides and auxiliary flame openings in its top, the portions of the outer wall between the main and auxiliary flame openings being imperforate. 90

5. A burner head having a main body portion and an offset portion arranged in substantial continuity, said body portion being provided with flame openings in its top and sides, and said offset portion having flame 95 openings in its sides only.

6. A burner head comprising a main manifold and an auxiliary manifold, said main manifold having a series of flame openings in its top and a series of flame openings on either side, the flame openings in the top terminating short of the length of the manifold 105 while the flame openings in the sides extend the entire length of the manifold.

Signed at Los Angeles in the county of Los Angeles and State of California this 110 September A. D. 1917.
